Primary Examiner — Katrina N Gonzalez*(74) Attorney, Agent, or Firm* — Sherrie Flynn; Coleman & Horowitz LLP(57) **CLAIM**

The ornamental design for a tile for animal communications, as shown and described.

DESCRIPTION

FIG. 1 is a perspective view of a tile for animal communications according to the design.

FIG. 2 is a top view of the tile of FIG. 1.

FIG. 3 is a front elevation view of the tile of FIG. 1.

FIG. 4 is a left side elevation view of the tile of FIG. 1.

FIG. 5 is a right side elevation view of the tile of FIG. 1.

FIG. 6 is a rear elevation view of the tile of FIG. 1; and,

FIG. 7 is a bottom view of the tile of FIG. 1.

The dashed dot dashed broken lines illustrate the bounds of the claim and the dashed broken lines illustrate portions of the tile for animal communications. The broken lines form no part of the claimed design.

1 Claim, 7 Drawing Sheets(56)
